(21) Appl. No.: **29/144,458**

Primary Examiner—Raphael Barkai

(22) Filed: **Jul. 5, 2001**

(74) Attorney, Agent, or Firm—Rader, Fishman & Grauer, PLLC

(51) LOC (7) Cl. **14-03**

CLAIM

(52) U.S. Cl. **D14/126**

DESCRIPTION

(58) Field of Search D14/125-136,
D14/239, 371, 374-382; 312/7.2; 348/836,
838, 180, 184, 325, 739; 248/917-924;
341/12; 345/104, 133, 156, 168, 87, 173

(56) **References Cited**

The ornamental design for a monitor television receiver, as shown and described.

U.S. PATENT DOCUMENTS

D324,382 S * 3/1992 Menei D14/126
D390,545 S * 2/1998 Chang D14/126
D411,990 S * 7/1999 Usui D14/126
D413,314 S 8/1999 Morimiya
D415,130 S * 10/1999 Chuo et al. D14/126

FIG. 1 is a perspective view of a monitor television receiver showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
